Filed July 8, 1968, Ser. No. 12,659

Term of patent 14 years

Int. Cl. D26—03

U.S. Cl. D48—31

FIGURE 1 is a perspective view of an outdoor mercury lamp lighting fixture showing our new design as viewed from the front of the fixture;

FIGURE 2 is a view similar to FIGURE 1 but taken on a different angle;

FIGURE 3 is a rear perspective of the fixture; and

FIGURE 4 is a view of the fixture similar to FIGURE 1 but showing the supporting bracket on an end of the fixture housing rather than on a side.

The light bulb is shown in broken lines in FIGS. 1, 2 and 4 for illustrative purposes only.

We claim:

The ornamental design for an outdoor mercury lamp lighting fixture, substantially as shown and described.
